UNITED STATES PATENT OFFICE.

ALBERT M. SCHAPPA AND ROBERT GOWDY, OF WESTFIELD, MASSACHUSETTS, ASSIGNORS TO THE PLANET COMPANY, OF WESTFIELD, MASSACHUSETTS, A CORPORATION OF MASSACHUSETTS.

FOLDING BOOTH.

Application filed October 5, 1920. Serial No. 414,737.

To all whom it may concern:

Be it known that we, ALBERT M. SCHAPPA and ROBERT Gowdy, both citizens of the United States of America, and residents of

5 Westfield, in the county of Hampden and State of Massachusetts, have invented a new and useful Folding Booth, of which the following is a specification.

Our invention relates to improvements in 10 folding or collapsible booths and the like, and more especially to booths used for voting purposes, and consists essentially of a plurality of frames, which frames are articulated together and adapted to be set 15 up to form the three sides of a booth or booth section, some booths being single, others double, and still others triple, etc., accordingly as the structure be designed to comprise a single section or two or more 20 sections, a shelf or shelves for such section or sections, and supporting and locking or fastening means between said frames and shelf or shelves, whereby when the latter are in place, they are safely and properly 25 supported and the frames are held securely in expanded or extended position, together with such auxiliary and subsidiary parts and members as may be necessary or desirable in order to render the structure complete 30 in every particular, all as hereinafter set forth.

The great increase in the number of voters, brought about by the granting of female suffrage, has rendered it desirable 35 and even necessary to provide means to accommodate or meet such increase, and means which can be easily and quickly placed in position for use before election, and as easily and quickly removed after the 40 voting is over; and the primary object of our invention is to assist in taking care of the new requirements, by providing a comparatively simple and inexpensive voting booth which occupies little space when 45 folder or collapsed, but can be set up in a comparatively short time and with comparatively little effort, and is then capable of serving practically the same purpose as either the built-in or permanent booth or 50 the non-collapsible booth. Our booth is in all respects capable of taking the place of the old type of booth, or of being employed as an auxiliary thereto.

Another object is to provide means where-

by the parts when expanded are locked in 55 place by the shelf in each booth or booth section, when said shelf is placed in position, and unlocked when said shelf is removed.

When our booth is set up it forms a stable structure that is provided with the customary and necessary shelf or shelves upon which to place and mark the ballots, and affords the required degree of privacy.

This booth can be made very light and is, therefore, easy to handle.

Inasmuch as the booth can be so compactly folded, it is possible to pack or store away a large number in a comparatively small space.

Other objects and advantages will appear 70 in the course of the following description.

We attain the objects and secure the advantages of our invention by the means illustrated in the accompanying drawings, in which—

Figure 1 is a top plan of a bi-section, folding booth which embodies a practical form of our invention, said booth being collapsed; Fig. 2, what may be termed a front edge elevation of said booth when collapsed; Fig. 3, a side elevation of the collapsed booth; Fig. 4, an enlarged, perspective view of one of the shelves of the booth; Fig. 5, a top plan, in partial section, of said booth in its expanded condition, or 85 when set up ready for use; Fig. 6, a front elevation of the expanded booth, the lower portions of the frames being broken off, and, Fig. 7, a top plan, on a reduced scale, of a single-section booth.

Similar reference characters designate similar parts throughout the several views.

Ordinarily it will be found more convenient to make our booth to include two sections, or, in other words, so to construct 95 the same that it will afford two voting places, thus being a double booth, and this form of the invention we will first describe in detail. It is, nevertheless, entirely feasible to make the folding booth in or with one 100 section so that when set up there is but a single voting place or compartment only, and also to make it up with more than two sections or places for individual voters.

The booth shown in Figs. 1, 2, 3, 5, and 6 105 comprises five, articulated frames, each consisting of a pair of uprights 1, a top cross-bar 2, an intermediate rail or cross-bar

3, and a cross-bar or brace 4 a short distance above the bottoms of said side pieces, and being provided with a panel 5 which closes the opening therein above the cross-bar 3 thereof, and two horizontal shelves 6 which are adapted to fit between the end and intermediate cross-bars 3 when the said frames are extended, together with means for supporting and securing such shelves in place 10 and locking the parts together. The cross-bars 2, 3, and 4 extend between the uprights 1 of each frame, and said uprights and cross-bars are rigidly secured together.

When set up this booth comprises an intermediate and two end frames and two back frames. The back frames at their adjacent ends are connected by two pairs of hinges 7 with the forwardly-extending, intermediate frame, two of said hinges directly connecting the inner upright 1 of one of said back frames with the rear upright 1 of said intermediate frame, and the other two hinges connecting the inner upright 1 of the other back frame with said rear upright of said intermediate frame. The hinges 7 are so connected with their uprights 1 that the back frames can be swung forward thereon into contact with the sides of the intermediate frame. Each end frame is connected by a pair of hinges 8 with one of the back frames at the outer end, such hinges being fastened to adjacent uprights 1 of said end and back frames in such a manner that said end frame can be swung against the back or outer side of said back frame.

The panels 5 may be of any suitable, but preferably light-weight, material, such as canvas, provided the same be opaque so as completely to enclose the shelves 6 on the back and ends, and prevent anyone outside of the booth from being able to see onto said shelves, from either the back or ends, and thus ascertaining in what manner the persons using the booth are marking their ballots.

The shelves 6 are of less width than the depth of the booth sections, as is customary in voting booths, so as to leave room for the voters to enter said sections for the purpose of using said shelves as supports for their ballots during the marking operation.

In the present case each shelf 6 is provided with three, flat hooks 9, two of such hooks being at the ends and the other at the back of said shelf. The hooks 9 are securely fastened to the top of the shelf, and extend out over the back and end edges thereof a sufficient distance to receive between said edges and the vertical parts of said hooks the cross-bars 3 upon which the protruding portions of said hooks are intended to be supported. The end hooks 9 on each shelf 6 are in offset relationship, and directly opposite each hook is a vertical slot 10 in the end of said shelf to accom-

modate the vertical part of the adjacent hook on the companion shelf, there being a shelf in each booth section, as previously pointed out. This obviates the necessity of cutting slots in the cross-bar or rail 3 of the intermediate frame, and the arrangement just described permits the shelves with their hooks to be used interchangeably.

The hooks 9 are designed to support the shelves 6 at the back and ends from the rails 3, and the latter must, therefore, be at the proper height to locate said shelves in convenient position for use. The hooks not only securely support the shelves from the rails 3, but lock said shelves to said rails 80 and the latter to the former, so that the structure is securely held in expanded or extended position, cannot be accidentally collapsed, and affords ample support for the shelves.

In setting up this booth, the two back frames are swung rearwardly or outwardly on the hinges 7 into a position at right-angles to the intermediate frame, and the end frames are swung forwardly or inwardly on the hinges 8 into parallel relation with said intermediate frame, and the two shelves 6 are placed in position with their hooks 9 in engagement with all five of the rails 3, each shelf being positioned with its rear edge in contact with one of the rear rails 3 and its end edges in contact with two of the other rails 3. The horizontal portions of the hooks 9 rest on the rails 3, and said rails are embraced between contiguous edges of the shelves 6 and the down-turned parts of said hooks. It will now be clearly seen that the shelves 6 are securely supported from the rails 3, and with the upper surfaces of said shelves on a level with the upper surfaces of said rails, and that, at the same time, the shelves with their hooks 9 lock the frames in position and securely hold them against independent movement. Two separate sections are thus provided for use in marking ballots by individuals who step into the sections, place their ballots on the shelves, and mark said ballots. The panels 5 shut off the view from three sides, so that the person occupying either section and marking his or her ballot can do so while secure from observation from any direction, the section being too narrow for the ballot to be observed over the shoulders of the person occupying the same.

The slots 10 in the edges of the shelves 6, which slots are, like the end hooks 9, in offset relationship, accommodate the down-turned parts of the adjacent hooks 9 which engage the rail 3 of the intermediate frame, and permits such edges to fit snugly within the expanded or open frames. The shelves are, of course, rectangular. The panel 5 on the intermediate frame is cut away, as represented at 11 in Fig. 5, to accommodate

the two hooks 9 which extend from opposite directions over the rail 3 of said frame when both shelves are in position. These panels being of fabric, it is not necessary to cut away the panels with which the end frames are provided, to accommodate the hooks 9 at the outer ends of the shelves 6, or the panels with which the back frames are provided to accommodate the hooks 9 at the rear edges 10 of said shelves, because such material will yield sufficiently to enable the down-turned parts of said hooks to be inserted in place between the rails 3 of said frames and the panels thereon.

15 To collapse the booth, it is simply necessary to raise the shelves 6 sufficiently to detach the hooks 9 from the rails 3 and remove said shelves, and then to fold the back frames forward against opposite sides of the intermediate frame and the end frames rearwardly against the back sides of said back frames. The folded frames and their shelves are now ready to be packed away or stored until again required for use.

20 25 The frames are preferably and customarily open beneath the rails 3.

The single section booth in Fig. 7 is very similar to what would remain of the bi-section booth, which has just been described, if 30 one of the back frames and the attached or connected end frame were removed from the remaining three frames, except that in the single-section booth the end frame which is connected with the back frame by the hinges 35 7 is positioned with its rear upright 1 in front of the rear upright 1 of said back frame, instead of against the outside of said last-mentioned upright. This, however, is an unimportant feature and the connection 40 45 might be similar to that shown in the other case.

When the Fig. 7 booth is collapsed the right-hand end frame is folded against the front side of the back frame and the left-hand end frame is folded against the back side of said rear frame.

In this latter construction the two end frames are of the same depth or rather they extend forward from the back frame the 50 same distance, when the booth is set up, while in the first construction the intermediate frame, although of the same depth as the end frames, does not extend forward so far, when the booth is set up, due to the fact 55 that said intermediate frame then sets in between adjacent ends of the back frames.

This again, is unimportant, moreover, the intermediate frame of the double booth could be made deeper if it were desired that the same extend forwardly as far as the end frames.

One or more sections can be added to the double booth herein first described, merely by adding one or more intermediate and back frames at either or both ends of the 60 structure just referred to, and attaching to the outer end or ends thereof the required end frame or frames.

More or less change in the shape, size, construction, and arrangement of some or all 70 of the parts of our booth, in addition to those hereinbefore specifically pointed out, may be made without departing from the spirit of our invention or exceeding the scope of what is claimed.

75 What we claim as our invention, and desire to secure by Letters Patent, is—

A folding booth comprising an intermediate frame, a pair of back frames hinged thereto and adapted to fold against opposite faces of said intermediate frame when collapsed, end frames hinged respectively to said back frames and adapted to fold against the outer faces of the latter upon being collapsed, each of said frames consisting in 80 part of vertical and horizontal rails, panels secured to portions of said frames, the panel on said intermediate frame being slotted at a predetermined point therein, removable shelves provided with slots in the end edges 85 thereof, said slots being arranged out of longitudinal alignment with respect to one another, and hook members secured to said shelves and extending beyond the end and rear edges thereof adapted for engagement 90 with certain of the horizontal rails of said frames to lock the latter in set-up and extended position, the end hooks being arranged in offset relationship but in longitudinal alignment with the opposite end slots. 95 100 and the inner opposed end hooks of said shelves being adapted for disposition through the slot in the panel to permit said hooks when positioned on the intermediate frame to be received in the slots of the contiguous shelves.

ALBERT M. SCHAPPA.
ROBERT GOWDY.
